UNITED STATES PATENT OFFICE.

JOSEPH M. FRANCIS, OF PROVIDENCE, RHODE ISLAND.

BUOY.

1,119,817.

Specification of Letters Patent.

Patented Dec. 8, 1914.

Application filed April 18, 1914. Serial No. 832,845.

To all whom it may concern:

Be it known that I, JOSEPH M. FRANCIS, a citizen of the United States, residing at Providence, in the county of Providence and 5 State of Rhode Island, have invented certain new and useful Improvements in Buoys; and I do hereby declare the following to be a full, clear, and exact description of the invention, such as will enable others skilled in 10 the art to which it appertains to make and use the same.

This invention relates to buoys and more particularly to a buoy applicable for attachment to a vessel for floating release therefrom when the vessel sinks, to indicate the 15 location of the vessel.

The primary object of this invention is the provision of a buoy as specified, which is composed of a plurality of buoyant sections 20 connected by flexible members, which sections are releasable for floating, from the vessel when the latter sinks, and the buoyant sections constitute separate buoys which are connected to the one next thereto by a cable 25 or other suitable flexible member for floating at various depths in the water, the uppermost of which sections carrying suitable signaling means for attracting attention to the buoy.

Another object of this invention is the provision of a novel means for locking the 30 various buoyant sections in engagement with the one next thereto, which locking means are releasable when the sections reach their floating limit for permitting the next section 35 to float upwardly, thereby forming a chain of buoys leading from the sunken vessel to the surface of the water.

With the foregoing and other objects in 40 view this invention consists in such novel features of construction, combination and arrangement of parts as will be hereinafter more fully described, illustrated in the accompanying drawings and claimed.

In describing the invention in detail reference will be had to the accompanying 45 drawings wherein like characters of reference designate like or corresponding parts throughout the several views, and in which—

Figure 1 is a side elevation of the improved buoy showing the various buoyant sections connected together, as the buoy is attached to a vessel. Fig. 2 is a central sectional view through a part of the lowermost 50 sections of the buoy and the support or retainer which is mounted upon the vessel

deck, showing the buoyant compartments disconnected for floating release one from the other, and showing the uppermost buoyant section in side elevation. Fig. 3 is a 60 cross sectional view on the line 3—3 of Fig. 1. Fig. 4 is a detail elevation of the upper portion of the uppermost of the buoyant sections. Fig. 5 is a detail view of the locking means for holding the uppermost buoyant sections in engagement with the one next thereto, and Fig. 6 is a detail view of the locking mechanism for holding the other of said sections connected.

Referring more particularly to the drawings, 1 designates the base or support of the buoy, which has annular arcuate flanges formed upon its lower end, and which is attached to the deck or side of a vessel in any suitable manner. The base or support 1 is 70 cylindrical shaped and it has a cable or flexible member 2 securely connected thereto, which cable is in turn connected to the base 3 of the section 4 of the buoy. When the buoy is positioned as is shown in Fig. 1 of 75 the drawings, the cable 2 is coiled within the interior of the cylindrical base 1, and the annular flange 5 which is formed upon the compartment 4 near the lower end of the same, rests upon the annular flange 6 80 which is formed upon the upper terminal end of the cylindrical base 1.

The section 4 of the buoy is divided into a plurality of compartments, one of which is hermetically sealed, for rendering the section 90 4 buoyant, and the other compartment 7 is provided for the retaining of a cable or flexible member 8, which is connected to the base 9 of the compartment in any suitable manner, and to the partition 10, which partition is formed in the section 11.

The section 11 of the buoy, like the section 4, is divided into compartments, one of which is hermetically sealed for rendering the section 100 buoyant, and the other of which is provided for the retaining of a flexible member or cable 12. The cable 12 is connected to a bail member 13, which bail member is connected at its ends, to rods 14 and 15, which rods are slidably mounted in 105 brackets 16 carried by the section 11, and extend longitudinally along the vertical sides of the same, being connected at their lower ends to links 17. The links 17 are in turn connected to arms 18 of the locking members 110 19. The locking members 19 are pivotally connected to brackets 20, which brackets are

secured to the outer surface of the sections 11, substantially equidistant from its ends as is clearly shown in Fig. 2 of the drawings.

The arms 18 of the locking member 19 have arcuate arms 21 connected thereto, which arcuate arms engage the upper end of the lever 22, when the sections 11 and 4 are connected as is clearly shown in Fig. 1 of the drawings. The levers 22 are pivotally carried by gears 23, which are connected to the outer surface of the section 4, and the levers have projections 24 formed thereupon intermediate their ends, which projections engage the upper surface of the annular flange 25. The annular flange 25 is formed upon the compartment 11 near the lower end thereof, and when the sections 11 and 4 are connected or in engagement with each other, the flange 25 rests upon the upper marginal edge of the compartment 4. The section 4 has plates 26 secured thereto and projecting upwardly from the upper end of the section, which plates are provided with recesses for the reception of the guiding pins 27 which are carried by the compartment 11.

The section 11 has an internal annular flange 30 formed near its upper end, upon the upper side of which rests the flange 31, which flange is formed upon the lower depending ballasted portion 32 of the buoyant section 33. The portion 32 of the buoyant section 33 has any suitable type of material mounted in the lower end of the same, for ballasting the section 33 to hold it in a vertical position while floating upon water. The section 11 has angle irons 34 secured to the outer surface thereof near its upper end, which angle irons are disposed diametrically opposite each other upon the surface of the section 11 and have their horizontal parts positioned upwardly and projecting transversely from the sides of the section 11 as is clearly shown in Fig. 5 of the drawings. Levers 35, which have buoyant balls 36 secured to their outer ends, are pivotally connected to brackets 37, which brackets are in turn secured to the flange 31 in any suitable manner. The inner ends of the arms 35, have recesses 38 formed therein, which recesses receive the outer edges of the horizontal arms of the angle members 34, for holding the buoyant section 33 connected to the buoyant section 11, when the various sections are connected as shown in Fig. 1 of the drawings.

The buoyant section 33 is divided into a plurality of compartments, the lower one of which is hermetically sealed for rendering the section buoyant, while the upper compartment is a container for combustible or volatile liquid such as kerosene or the like, and the compartment has a burner 40 communicating therewith, in the usual manner, and having any suitable type of capillary means for feeding the combustible or volatile

fuel through the burner for the ignition of the fuel for producing a light and smoke. A shade or protector 41 is positioned about the burner 40 to prevent wind or water from extinguishing the flames when the same is 70 lighted.

The protective shade 41 has a bracket or support 42 connected thereto, which bracket is substantially the shape of an inverted U, and has its terminal end secured to the protective shade 41 in any suitable manner. A bell 43 is suspended from the connected portions of the bracket, directly above the upper end of the protective shade 41.

In the operation of the improved signaling buoy as heretofore described, the buoy is attached to the deck of a vessel to one side of the boat, so that in case the vessel sinks, the compartments 4, 11 and 33 will float free from the base or retainer 1 and 85 when the sections have reached the limit of the cable 2, the section 4 will be restrained from rising to a higher elevation or a greater distance from the vessel and the restraining of the upward movement of the 90 section 4, will cause the buoyancy of the balls 36 carried upon the arms 35 to act, moving the levers 35 upwardly, and causing the transverse arms of the angle members 34 to be free from engagement with the recesses 38 formed in the ends of the arms, and this will release the buoyant section 33 from connection with the section 11, permitting the section 33 to float upwardly until the limit of the cable 12 has been reached, 100 when the buoyancy of the section 33 will pull upon the bail member 13, causing the latter to actuate the rods 14 for moving the arcuate arms 21 of the locking members 19 out of engagement with the upper terminal 105 ends of the levers 22, after which the levers will fall downwardly, releasing the projections 24 thereon from engagement with the flange 25 and permitting the section 11 to float free from the section 4 until the limit 110 of the cable 8 has been reached, in this manner approximately the depth of water in which the vessel has sunk may be determined, owing to the number of the sections which are floating. The rocking of the section 33 by the waves will ring the bell 43 causing the same to sound an alarm, and when the light is ignited, the smoke therefrom will further attract attention to the buoy in day time, while the rays of light 115 generated by the ignition of the combustible fuel will attract attention thereto at night, acquainting persons of the location of the sunken vessel.

If it is desired, an electric light operable 125 intermittently by the closing of the contact, which contact might be closed by the rocking of the section 33 may be attached to the section for providing an intermittent light signal for attracting attention to the buoy. 130

If it is so desired, a telephone or telegraph system, or any other suitable type of signaling apparatus may be attached to the buoy, so that in cases of the sinking of a ship, communication may be established with persons upon the ship through the medium of the telephone or telegraph, or signaling mechanism.

If it is so desired, a buoy constructed in accordance with the drawings and description heretofore set forth, may be attached to the side of a submarine vessel, and the releasing of the buoy be controlled by suitable leverage mechanism (not shown) which is controllable from the interior of the submarine, so that in cases where the submarine was incapacitated beneath the water, the buoy might be released for carrying a distress signal to ships or vessels sailing upon the surface of the water.

From the foregoing description, taken in connection with the accompanying drawings, the advantages of the construction and of the method of operation of the improved buoy will be readily apparent to those skilled in the art to which this invention appertains and, while in the foregoing description the principle of the operation has been described, together with various features of construction, it is to be understood that certain minor features of construction, combination, and arrangement of parts may be altered to suit practical conditions, provided such alterations are comprehended within the scope of what is claimed.

What I claim is:—

1. In a signaling buoy, a plurality of buoyant compartments arranged in alignment with each other and connected to the one next thereto for floating release therefrom at predetermined times, and a cable connecting the lowermost of said buoyant sections to a vessel.

2. In a signaling buoy, a plurality of buoyant compartments connected together

by lengths of cable, means for holding said buoyant compartments in direct connection with each other releasable by buoyancy of various compartments.

3. In a signaling buoy, a plurality of buoyant compartments connected together by lengths of cable, means for holding said buoyant compartments in direct connection with each other releasable by buoyancy of various compartments, and signaling means carried by the uppermost of said buoyant compartments.

4. In a signaling buoy, a plurality of buoyant sections connected by cables to each other, arms pivotally connected to one of said sections and having buoyant members formed upon their outer terminal ends, the inner end of said arms engaging the angle brackets carried by another of said sections for holding two buoyant sections connected until released by the upward movement of said arms by the buoyant members carried by their outer ends for releasing said compartments for separate floating.

5. In a signaling buoy, a plurality of buoyant sections connected by cables to each other, arms pivotally connected to one of said sections and having buoyant members formed upon their outer terminal ends, the inner end of said arms engaging the angle brackets carried by another of said sections for holding two buoyant sections connected until released by the upward movement of said arms by the buoyant members carried by their outer ends for releasing said compartments for separate floating, signaling means carried by the uppermost of said compartments, and a cable connecting the lowermost of said compartments to a vessel.

In testimony whereof I affix my signature in presence of two witnesses.

JOSEPH M. FRANCIS.
